UNITED STATES PATENT OFFICE.

BENJAMIN S. McCLELLAN, OF CHICAGO, ILLINOIS.

WINDOW.

1,329,003.

Specification of Letters Patent. Patented Jan. 27, 1920.

Application filed January 17, 1913. Serial No. 742,567.

To all whom it may concern:

Be it known that I, BENJAMIN S. McCLELLAN, a citizen of the United States, and a resident of Chicago, in the county of 5 Cook and State of Illinois, have invented certain new and useful Improvements in Windows; and I do hereby declare that the following is a full, clear, and exact description thereof, reference being had to the accompanying drawings, and to the letters 10 of reference marked thereon, which form a part of this specification.

This invention relates to an improved construction in windows having sliding sashes and embracing parts in the nature of weather strips adapted for maintaining tight joints between the sides of the frame and the side edges of the sash, while permitting free movement of the sash relatively 20 to the frame.

My invention is more particularly designed for, and applicable to, the windows of passenger cars or coaches, but the features constituting the invention are equally 25 applicable to windows used for other purposes.

The invention consists in the matters hereinafter described and pointed out in the appended claims.

30 In the accompanying drawings illustrating my invention—

Figure 1 is a view in side elevation of a part of the side or jamb of the window frame and of the upright part or side member of a sash which engages the frame;

Fig. 2 is a plan section taken on line 2—2 of Fig. 1;

Fig. 3 is a vertical section taken upon line 3—3 of Fig. 2;

40 Fig. 4 is a vertical section taken upon line 4—4 of Fig. 2;

Figs. 5 and 6 are plan sections showing different forms of construction in the resilient pressing device on the sash.

45 As shown in said drawing, the side member or jamb of the window frame includes a wooden vertical member 5 having applied to its exposed face a flat metal plate 6. Secured against the plate 6 are two metal strips 7 and 8 constituting outer and inner guides or stops, and forming with the plate 6 a

50 guide-groove to receive the outer edge of the upright side member 9 of the window

sash. The metal strip 7, forming the outer stop, is provided with a base flange 7^a, which 55 extends at right angles to the body of the strip and is secured against the plate 6 by means of screws 7^b or other suitable fastening means. The strip 8, forming the inner strip, is shown as consisting of a piece of 60 sheet metal bent into U-shape, as illustrated, and provided with a flat base portion 8^a which rests against the plate 6 of the upright frame member 5 and terminates at its inner edge in an outwardly extending folded 65 part 8^b, which forms with the stop portion 8^a a groove for another sash. The U-shaped stop forming portion 8 is shown as secured to the frame by means of screws 8^c inserted therethrough and through the plate 6 into 70 the wood backing 5 of the frame. The construction illustrated in the frame, by which the guide groove for the sash is formed by metal plates and strips, is such as will be used in metal car construction, wherein the 75 exposed parts of the frame are formed of sheet metal.

Attached to the outer face of the upright side member 9 of the sash, near its side edge which engages the guide groove of the 80 frame, is a metal strip 10, arranged to overlap the metal stop strip 7, which is interposed between said strip 10 and the adjacent face of the sash member. Said strip 10 is secured at one margin to the sash member 9, conveniently by screws 10^a, 10^b, and has bearing contact at its free or unattached 85 marginal part against the outer face of said stop strip 7. Said sash member is provided, adjacent to its side margin which engages the frame, with a longitudinally extending recess or rabbet 11, located beneath the strip 10 and adapted to receive the stop strip 7; this construction enabling the strip 10 to be made of a flat piece of sheet metal, arranged 90 in the plane of the side of the sash member to which it is secured.

Referring now to the form of construction shown in Figs. 1 to 4, a resilient or elastic pressing member 12 is secured to the marginal part of the sash member 9 in position to press outwardly against and have sliding engagement with the inner face of the stop member 7. The elastic pressing member thus arranged, serves to press or hold the 105 strip 10 against the outer face of said stop

member; both the strip 10 and said resilient member 12 being adapted for sliding contact with the stop member 7 when the sash is moved relatively to the frame. As shown 5 in said Figs. 1 to 4, the resilient member 12 has the form of a curved metal spring, seated in a recess formed in the rabbeted part 11 of the sash member 9. Said spring is arranged with its convex side in bearing contact with the said stop strip 7, while its ends are loosely connected with the sash in a manner permitting its central part to bend or flex inwardly. As illustrated, the spring 12 is mounted in a casing 13, of channel or 15 U-shape, which is secured in a recess formed in the rabbeted marginal part of the sash member 9 and said casing is provided with two transverse metal studs or pins 13^a, against which the ends of the spring member 20 rest or bear. The ends of said spring are bent to form inwardly curved parts 12^a, 12^a adapted for engagement with the said studs 13^a, 13^a, in a manner to prevent the spring from becoming detached or falling 25 out of the said casing.

In the operation of the device, as clearly shown in Figs. 1 to 4, the spring member 12 presses constantly against the inner face of the stop strip 7, and by its pressure on said 30 stop strip tends to shift or move the body of the sash member 9 in a direction away from the stop member and to draw or press the strip 10 of said sash member into close bearing or contact with the outer face of 35 said stop member 7. A tight joint will thus be always maintained between the stop strip 7 and the strip 10, while at the same time the pressure exerted by the spring member 12, by which the strips 7 and 10 are held in contact with each other, would not be so great 40 as to prevent the sash from being easily moved in raising or lowering the same. The stop strip 7 and strip 10 on the sash, coacting in the manner described with the spring 45 12, serve in the nature of weather strips to maintain always a tight joint between the side of the sash and side of the frame, while at the same time serving to prevent any shaking or rattling of the sash.

50 In Fig. 5 I have shown a modified form of construction in a resilient or spring member on the sash, adapted to constitute a pressing means acting on the inner face of the stop member. In this instance the resilient 55 pressing means consists of a longitudinally extending strip of soft rubber 15, inserted in a recess in the sash member 9, and a longitudinally extending sheet metal strip 16, applied against the outer face of the rubber strip 15 and held by the latter with its outer face in bearing contact against the said stop strip 7. The means shown in 60 said Fig. 5 for holding the rubber and metal strips 15 and 16 in place, consists of screws, 65 one of which is indicated by 16^a, inserted

through the said strips and into the sash member 9, the metal strip 16 being countersunk to receive the head of the screw, and having a hole therein for the screw, larger in diameter than the screw, so that the head 70 of the screw will constitute a stop to limit the outward movement of the metal strip 16, while said strip will be yieldingly supported by the rubber strip 15 and will be pressed by the action of the latter against 75 the said stop strip 7.

In Fig. 6 I have shown still another form of construction in the resilient pressing member of the sash. In this instance, a strip 17 of felt, plush or other compressible 80 and elastic or yielding fabric is inserted in a longitudinal groove 17^a formed in the outer face of the rabbeted part of the sash. The said strip 17 is made of such thickness 85 as to press or bear against the inner face of the stop member 7, with the same results as hereinbefore described in connection with the other forms of resilient pressing devices illustrated.

In connection with both of the forms of 90 pressing devices shown in Figs. 5 and 6, it is to be understood that the same may extend either the entire length of the sash member 9 or only a part of the length of the same, and in connection with the pressing devices shown in Figs. 1 to 4, it will be understood that the sash member 9 may be provided with either one, or a plurality of, such pressing devices.

It is to be understood that a device 100 embodying the features of my invention hereinbefore described, may be varied in its details from the form of such devices illustrated in the accompanying drawings, and I do not, therefore, desire to be limited to 105 the specific features of construction and design illustrated, except so far as the same may be set forth in the appended claims as constituting parts of my invention.

I claim as my invention:

1. The combination with a window frame and sash, of a metallic stop strip on the frame, a metal strip on the sash arranged in overlapping relation with the stop strip on the frame, and resilient pressing means 115 on the sash having sliding engagement with the stop strip and acting on said stop strip in a direction to press the strip on the sash into contact with the said stop strip.

2. The combination with a window frame 120 and a sash provided with a rabbet in its side face, of a metal stop strip on the frame, extending into the said rabbet, a metal strip attached to the sash and extending over said rabbet in overlapping relation with the 125 stop strip, and a resilient pressing member seated in the rabbeted part of the sash and acting on the stop strip in a direction to press the strip on the sash yieldingly against the said stop strip.

3. In a device of the class described a weather stop on a window frame, a member on the sash overlapping said stop, and resilient means secured to the sash and bearing against said stop to hold said member and stop in close relation.

5 In testimony that I claim the foregoing as

my invention I affix my signature in the presence of two witnesses, this 4th day of January, A. D. 1913.

BENJAMIN S. McCLELLAN.
